UNITED STATES PATENT OFFICE

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY

INKING DEVICE FOR MARKING MACHINES

Application filed October 10, 1927, Serial No. 225,211. Renewed May 1, 1930.

This invention relates to marking machines for use in marking sheet material such as parts of boots and shoes and is illustrated as embodied in a machine of the type shown in 5 Letters Patent of the United States No. 1,172,897, granted February 22, 1916, upon the application of F. W. Merrick.

In marking machines of the type under consideration the work is supported in horizontal position upon a platen or work table. The marking is done by means of type wheels or a die carried up and down upon an oscillating head from an inoperative position to a position in contact with a piece of work on 15 the platen. Ink is applied to the marking device between the oscillations of the marking head, usually by means of a pad which is oscillated from an inoperative position to a position underlapping the marking device 20 when the latter is in its elevated position. Such an arrangement has proved to be satisfactory when the marking devices used are of small dimensions, such as a row of type or the like, but, when it is desired to use the 25 machine for marking large designs upon shoe uppers to guide in the application of fancy stitching thereon, difficulty has been experienced because of the unusually wide pad needed to apply ink to the whole surface of 30 the large marking die.

Accordingly, an object of the present invention is to provide an improved arrangement for applying ink to a marking device by which the inking of dies of large dimensions may be facilitated. In the illustrated arrangement, in accordance with features of the invention, the inking pad is swung upwardly and slid outwardly into operative position so that said pad is brought to a position fully underlapping a marking device even of large size. With this arrangement there is no interference with other parts of the machine when the pad is manipulated, either as it moves back to inoperative position or when it is moved out of operative or inking position.

For best results the inking pad must be applied to the die firmly and evenly without any slurring thereof, and another feature of the invention resides in an organization by

means of which the sliding movement of the pad is completed prior to the contact of the pad with the die, thus pressing the pad evenly against the die by means of a simple swinging movement of the pad carrier.

55

In the drawings,

Fig. 1 is a side elevation of a marking machine to which my improved inking pad has been applied, showing the pad in inking position, and

60

Fig. 2 is a similar view of the parts, shown in outline, in the position in which the marking device is in contact with the work and the inking pad has been moved back to inoperative position.

65

The machine illustrated comprises a frame made up of side members 10 and 12 between which are mounted a drive-shaft 14 and a crank-shaft 16 geared thereto as in said patented machine and arranged to oscillate a walking beam 18 pivotally mounted between said frames. At the outer end of the walking beam there is hung an upright member 20 carrying at its lower end a marking device 22 in the form of a flat die of substantial dimensions, as large as the palm of the hand, for example. The upright member 20 is supported for movement in parallel, substantially vertical planes by means of a link 24 interposed between the frame and said upright member.

70

Pieces of work 70 are supported upon a work table or platen 30 carried at the outer end of an arm 32 which is secured to the side frames 10 and 12, and the platen 30 is arranged for control automatically to adjust itself to varying thicknesses of work by means of an arm 34 and other parts more fully illustrated and described in the patent to Merrick to which reference has been made above. The machine is provided with a suitable clutch controlled through a treadle rod 36 and may be caused to go through a single cycle of movement or successive cycles at the will of the operator.

75

95

Because of the considerable breadth of the marking device 22, a pad sufficiently wide to apply ink to the whole of said die, mounted for simple swinging movement, as in the machine of the Merrick patent, would inter-

ference with other parts of the machine. Accordingly, in the illustrated attachment, which may be substituted for the inking device of a machine of the Merrick patent, the inking pad 40 is slidingly mounted, by means of a dovetail connection, upon a flat plate 42 carried at the outer end of a swinging arm 44, thereby providing an arrangement for, in effect, extending the length of said arm 10 when moving the pad to inking position and shortening it when the marking head descends to avoid interference between the pad and the work-support. The inner end of this arm is pivoted at 46 between the side frames 15 10 and 12, and the arm is swung in and out through a series of positions occupying definitely related intersecting planes, by reason of its connection to the upright member 20 through a link 48. This link 48 is pivotally attached at its lower end to the arm 44 and at its upper end to a stud 50 having integral eccentric pivots thereon mounted in a projecting member 52 which is integral with the upright member 20. By adjusting this stud 25 50, the contact pressure between the pad and the die 22 may be controlled. The inking pad 40, besides being swung outward by the arm 44, is also controlled by means of links 54, 56 and 58 which are interconnected at their adjacent ends and are arranged to alter 30 the relation of the pad 40 and the arm 44 by imparting a sliding movement to the inking pad 40 along the swinging arm 44. To this end the outer end of the link 54 is pivotally connected to the under side of the inking pad 35 at 60 and the inner end of the link 58 is loosely pivoted upon the drive shaft 14. A fulcrum 62 for an intermediate part of the middle link 56 is provided by means of a depending finger 64 upon the swinging arm 44. It is to be understood that no power is imparted 40 to links 54, 56 and 58 from the drive shaft 14 and that the sliding of the inking pad 40 with relation to the swinging arm 44 results solely 45 from the swinging movement of the pad carrying arm 44 with respect to the fixed fulcrum provided by the drive shaft 14. As a result, when the marking device 22 starts to move down into marking position the swinging arm 44 is turned on its pivot 46 and at the 50 same time the inking pad 40 is moved inwardly along the upper face of the rigid carrying plate 42, thus shortening the distance between the outer end of the pad and the pivot 46. This movement will carry the 55 pad to the position shown in Fig. 2 where it is out of the way of the marking die 22 as the latter is applied to a piece of work 70 supported upon the platen 30 and interference 60 between the inking pad and other parts of the machine, specifically the platen 30, has been avoided. When the marking die moves up to its inoperative position shown in Fig. 1, the inking pad is again swung upwardly 65 and is slid forward along the arm 44 to cause

it wholly to underlap the face of the marking die. In so doing it is moved into contact with the marking die to provide ink therefor prior to the next succeeding marking operation. It will be seen that the relation of the links controlling the sliding movement of the ink pad 40 (and specifically the horizontal relation of the fulcrum 62 and the pivotal connection between the links 54 and 56) is such that the sliding movement of said pad has been completed before the pad is brought into contact with the marking die 22, thus avoiding any tendency to smear ink over the undercut portions of the marking die and giving to the pad a simple movement of impression against the marking die.

Having thus described by invention, what I claim as new and desire to secure by Letters Patent of the United States is:

1. In a marking machine having a marking device and a platen which are relatively movable to bring the marking device into contact with a piece of work supported on the platen, a pad for applying ink to the marking device, a support for said pad, and means for sliding said pad on the support and at the same time swinging the support to bring the pad into contact with the marking device when the latter is separated from the platen.

2. In a marking machine having a marking device and a platen which are relatively movable to bring the marking device into contact with a piece of work supported on the platen, a pad for applying ink to the marking device, a swinging support constructed and arranged to carry said pad from a position out of the range of relative movement of said marking device and platen into a position in contact with the marking device, and means for sliding said pad on said swinging support to reduce the space required for said swinging movement.

3. In a marking machine having a marking device and a platen which are relatively movable to bring the marking device into contact with a piece of work supported on the platen, a pad for applying ink to the marking device, and means for moving said pad from an inoperative position to a position in contact with the marking device comprising a support fulcrumed for swinging movement into and out of the path of relative movement of the marking device and platen actuated by said relative movement, and additional means for moving said pad relatively to said support to bring it into a position opposite the marking device as it is moved for engagement therewith.

4. In a marking machine having a marking device and a platen which are relatively movable to bring the marking device into contact with a piece of work supported on the platen, means for supplying ink to said marking device comprising a pad, a swing-

ing arm supporting said pad, means for swinging said arm to carry the marking pad into a position between the marking device and the platen when the latter are in separated position and additional means for extending the length of said arm to bring said pad into a position fully underlapping the marking device.

5. In a marking machine having a marking device and a platen which are relatively movable to bring the marking device into contact with a piece of work supported on the platen, means for supplying ink to said marking device comprising a pad, a swinging arm supporting said pad, means for swinging said arm to carry the marking pad into a position between the marking device and the platen when the latter are in separated position, and additional means constructed and arranged to reciprocate the marking pad on said swinging arm as it moves back and forth from operative to inoperative position in order to avoid interference between the pad and other parts of the machine.

25 6. An attachment for supplying ink to a marking die on an existing machine having a platen and a vertically movable support for the marking die, said attachment comprising a swinging arm, an inking pad slidably carried thereby, means for connecting said arm to the movable die carrying member, and additional means for sliding the pad upon the arm as it is swung into position to apply ink to the marking die.

35 7. In a marking machine, a frame, means for marking a piece of work comprising a supporting platen and a marking die, one of which is movably supported on said frame, a pad for applying ink to the marking die movable from a position out of the path of movement of the movable element in the marking machine to a position where the pad is interposed between the die and the platen to apply ink to the die, means pivotally attached to said frame constructed and arranged to underlie the pad to support it for movement through a series of positions occupying definitely related planes such as to bring it from an inoperative position to an inking position, and additional means for controlling the path of movement of the pad constructed and arranged to vary the position of the pad upon said pad supporting means.

55 8. In a marking machine having a marking device and a work supporting device which are relatively movable to bring the marking device into contact with a piece of work supported on the work support, a pad for supplying ink to the marking device, a pivoted pad support slidably supporting said pad, and means for swinging said pad support concurrently sliding said pad on said support to move the pad from an inoperative position out of the range of movement of said device to a position in which the mark-

ing pad is interposed between the two devices and is in contact with the marking device, said means being constructed and arranged to combine sliding and swinging movements of the pad so correlated that the sliding movement is completed prior to the contact of the pad with the die.

9. In a marking machine, a work supporting platen, a marking die adapted to be moved substantially vertically against a piece of work on said platen and then away from said platen, a pad for applying ink to the marking die slidably supported upon an arm which is mounted to swing into and out of the path of movement of the die, and means for controlling the sliding movement of the pad comprising a lever pivoted on a fulcrum below the plane of the die and a link connected to one end of said lever and to the pad, the point of connection between said lever and link being substantially horizontally opposite the fulcrum of the lever when the pad is in inking position whereby the movement of the pad as it is brought into contact with the die will be entirely a swing movement.

10. In a marking machine having a marking device and a platen which are relatively movable to bring the marking device into contact with a piece of work supported on the platen, a fixed frame supporting said marking device and platen, a pad for applying ink to the marking device, a pad-support pivoted on said frame, means for swinging said support to carry said pad into contact with said marking device when it is separated from the platen and for swinging said support to carry the pad out of the range of relative movement of said marking device and platen, and means for changing the relation of said ink pad to said support during said latter movement thereby to avoid interference between the outer end of the pad and the platen.

11. In a marking machine having a marking device and a platen which are relatively movable to bring the marking device into contact with a piece of work supported on the platen, a frame, a pad for applying ink to the marking device, a pad-support pivoted on said frame, means for swinging said support to carry said pad into contact with said marking device when it is separated from the platen and for swinging said support to carry the pad out of the range of relative movement of said marking device and platen, and means for changing the relation of said ink pad to said support during said latter movement thereby to avoid interference between the outer end of the pad and the platen, said relation-changing means comprising a member coacting with a portion of the frame.

12. In a marking machine having a marking device and a platen which are relatively

movable to bring the marking device into contact with a piece of work supported on the platen, a pad for applying ink to the marking device, a frame, a supporting arm for said pad pivoted on the frame for swinging movement, means for swinging said pad-support to bring the pad into contact with the marking device when the latter is separated from the platen and for swinging said pad-support out of the path of relative movement of the marking device and platen, and additional means for shortening said pad-supporting arm during said swinging movement to prevent interference between the outer end of the pad and the platen.

13. In a marking machine, a frame, a platen for supporting a piece of work, a marking device movably supported on said frame for movement toward and away from said platen, an ink pad for applying ink to said marking device, a pad-supporting arm pivotally mounted on said frame at one side of said path of movement of the marking device, a connection between said marking device and said pad-supporting arm for swinging the pad into contact with the marking device when the latter is in a position separated from the platen and for swinging the pad out of the path of movement of the marking device as the latter moves toward the work, and means for shortening said pad-supporting arm during said latter swinging movement to prevent interference between the outer end of the pad and the platen.

14. In a marking machine, a frame, a platen for supporting a piece of work, a marking device movably supported on said frame for movement toward and away from said platen, an ink pad for applying ink to said marking device, a pad-supporting arm pivotally mounted on said frame at one side of said path of movement of the marking device, a connection between said marking device and said pad-supporting arm for swinging the pad into contact with the marking device when the latter is in a position separated from the platen and for swinging the pad out of the path of movement of the marking device as the latter moves toward the work, and means for shortening said pad-supporting arm during said latter swinging movement to prevent interference between the outer end of the pad and the platen, said means being operated solely by the movement of the pad-carrying arm with respect to the frame.

In testimony whereof I have signed my name to this specification.

PERLEY R. GLASS.

CERTIFICATE OF CORRECTION.

Patent No. 1,808,812.

Granted June 9, 1931, to

PERLEY R. GLASS.

It is hereby certified that error appears in the printed specification of the above numbered patent requiring correction as follows: Page 1, line 45, for "of" read to; page 2, line 90, claim 1, before the word "support" insert swing-
ing; and that the said Letters Patent should be read with these corrections
therein that the same may conform to the record of the case in the Patent
Office.

Signed and sealed this 22nd day of September, A. D. 1931.

(Seal)
